SIGNAL

Karl J. Mislin, Kansas City, Mo.

Application June 10, 1935, Serial No. 25,841

4 Claims. (Cl. 177—339)

This invention relates to signal structures of the type wherein it is desired to present visible indicia and wherein is employed a reflecting surface disposed at an angle so that the remaining and associated parts of the signal will operate therewith in a simple, novel and effective manner.

One of the important aims of this invention is to provide a signal having as a part thereof, an unique case or housing which is provided with a plurality of compartments, all having panels forming one wall thereof which are positioned so that the indicia on said panels are reflected from a suitable surface that is a part of the housing per se.

Another object of this invention is to provide a signal having unique electrical circuits wherein is disposed means for making and breaking the circuits at desired times and means for indicating that any electric lamps within the circuits are inoperative.

A yet further object of the invention is the provision of signal structure of the type that is especially adapted for use in indicating the direction of turn which an automobile is about to make and having means for making and breaking the circuits both manually and automatically so that after the turn has been made, the signal will be rendered inoperative.

A large number of minor objects of the invention will appear during the course of the following specification, referring to the accompanying drawing, wherein:

Figure 1 is a perspective view of a signal housing and associated parts made in accordance with the present invention.

Fig. 2 is a vertical cross section through the same.

Fig. 3 is an edge elevation of the steering wheel of an automobile, showing the same equipped with one of the switches forming a part of the signal structure.

Fig. 4 is a top plan view of the steering wheel showing the switch operating members in place, and,

Fig. 5 is a wiring diagram illustrative of the electrical circuits that may be employed in the signal.

Signal structures such as this invention contemplates may be employed as indicating signals on automobiles, as traffic signal devices, and wherever it is desired to employ a visible signal that is actuated by the making and breaking of an electric circuit, the novel feature of the signal housing being the inclusion of the uniquely disposed reflector or reflectors which serve to

render the otherwise invisible indicia visible when appropriate electric lamps are burning.

In the drawing, the invention is embodied in an automobile direction signal and the housing 8 is partitioned as at 10 to provide two main compartments 12 and 14 that are bottomed by panels 16 and 18, having formed thereon indicia 20 in the nature of arrows which point in opposite directions, as shown. Any other character of indicia might be created on panels 16 and 18 so long as the same visibly indicate to the observer of the signal the message which the user thereof desires to convey. A supplemental compartment 22 forms a part of housing 8 and in the operation of the signal, is common to both compartments 12 and 14 in so far as the lights therein are concerned. Panels 16 and 18 should be inclined or angled out of the horizontal so that the images of the indicia 20 are reflected from substantially the same area of a reflector 24. This reflector 24 is angled so that when the housing 8 is secured to the automobile, those approaching the same will be able to see the image of the indicia when the appropriate lights within the housing 8 are burning.

Supplemental compartment 22 has a panel 26 forming the bottom thereof and the word "turn" is the indicia 28 that is formed to be reflected from reflector 24 when either one of the two light bulbs 30 and 32 in supplemental compartment 22 is burning.

When this signal casing is used on the rear of the automobile, it is desirable to include therein a small window 34 that serves as a tail light when bulb 36 is burning. Another window 38 is provided to serve as a stop light when electric bulb 40 is burning. These windows 34 and 38 are disposed on each side of a central area upon reflector 24 and because of the angularity of panels 16 and 18, any reflected images originating on said panels will be between tail light and stop light windows 34 and 38 respectively. It will be observed that when the lights 30 and 32 are burning the word "turn" is reflected from a place on the reflector immediately adjacent to the zone thereon, from which indicia 20 are reflected.

It is desirable when using this signal on automobiles to indicate the direction of turn prior to the actual turning and then to automatically cut off the indicating signal after the turn has been made. To do this, the invention provides an unique switch 42 shown diagrammatically in Fig. 5 and arranged to make and break circuits as hereinafter set down. This switch may be affixed to the steering column 44 and its arm 46 should have opposed, laterally extending 55

throw bars 48 that are engageable by cams 50 carried by some part of the steering wheel. The actual operation of this structure is unique in that when the throw bars 48 have been manually moved to a right or a left position indicated by dotted lines in Fig. 4 the switch is closed. Cam 50 will thereafter be depressed by bar 48 as the wheel is being turned in one direction to steer the automobile to the right or left as the case may be. A spring 52 returns the respective cam 50 after it has been depressed and after the bar 48 has passed it and when the wheel is returned, inclined end 54 will engage throw bar 48 to force it back to the switch opening position.

15 Since the electrical circuits employed in this signal are important and since it is an object of the invention to provide an audible signal to indicate when the electric lamps in the system have failed, reference will now be had to the diagrammatical illustration of the circuits and the like that are best suited for use in the system.

Where the tail light 36 is employed, an ordinary switch 56 is used and the circuit which closes this lamp is from ground G, battery B, wire 58, light 36 and wire 60, back to the ground G.

Stop light 40 should be operated as the driver uses the brake of his car and the brake pedal 62 forms a switch opening element so that when the 30 said switch is closed, the circuit through stop light 40 is as follows: ground G battery B, wire 64, wire 66, closed switch 68, bulb 40 and wire 70.

Assuming now that it is desired to indicate a right turn, bulb 72 in compartment 12 will be 35 placed in circuit by the throwing of switch 42 where switch point 74 is in contact with switch point 76, switch point 78 is in contact with point 80 and switch point 82 is in contact with point 84. With the switch in this position, the circuit 40 is as follows: from ground G through battery B, wire 64, closed points 80 and 78 and 74 and 76, wire 86, coil 88, wire 90, closed points 82 and 84, wire 92, wire 94, bulb 72 to the ground. Bulb 30 is simultaneously lit because wire 96 connects 45 wire 92 and bulb 30 is grounded.

When switch 42 is thrown to indicate a left turn, switch points 98 and 100 are together as are switch points 102 and 104 and 106 and 108.

The circuit through bulbs 32 and 110 may be 50 traced as follows: battery B which is grounded, wire 64, closed points 104 and 102, closed points 106 and 108, wire 86, coil 88, wire 90, closed points 98 and 100, wire 112, to bulbs 32 and 110 respectively and thence to the ground.

55 The strength of the current passing through coil 88 when the lights are in workable condition is strong enough to set up a magnetic pull upon armature 114 that will overcome the tension of spring 116 to the extent that points 118 and 120 are held apart. If a bulb burns out, this magnetic force is decreased immediately and spring

116 draws switch point 118 against point 120. Buzzer 122 will then be in the circuit regardless of which way switch 42 is set because wire 124 joins the common wire 86 and from this point the circuit is completed through closed points 118 and 120, wire 126, buzzer 122 and wire 128 to the ground. Obviously, the buzzer will be actuated to indicate that one of the bulbs, which the operator cannot see, is not functioning.

Having thus described the invention, what is 10 claimed as new and desired to be secured by Letters Patent is:

1. In a signal of the character described having an inclined reflector forming one wall thereof, a housing having a partition dividing the 15 same into a plurality of compartments; panels having appropriate indicia thereon closing one side of the compartments respectively; and illuminating means within each compartment respectively; all of said panels being disposed so 20 that the image of the indicia of the respective panels is reflected from the reflector when the illuminating means in the compartments is in operation, certain of said panels being disposed at an angle whereby the images of the indicia of said panels are reflected from substantially the same area of said reflector when the signal is operated, said housing having a supplemental compartment therein provided with illuminating 25 means and an indicia-bearing panel, the image of the indicia of the supplemental compartment being reflected from a zone immediately adjacent the zone of the reflector reflecting the image of the indicia of the aforesaid angled panels.

2. In a signal of the character described having a reflector a housing having a partition dividing the same into two compartments; inclined panels forming the sides of a triangle and each having indicia therein closing the lower sides of the compartments; a supplemental compartment adjacent the first mentioned compartments having indicia formed in one side thereof; whereby the images of the respective indicia may all be cast upon the reflector; and an electric lamp in each compartment respectively.

3. In a signal of the character described, an inclined reflector; a housing having a plurality of inclined panels overhanging the said reflector; indicia formed in said inclined panels; electric lamps within the housing to cause the images of said indicia to be reflected from the said reflector; windows formed in said reflector to one side of the images of the indicia that are reflected therefrom and illuminating means behind said windows.

4. In a signal of the character described having a plurality of panels with indicia formed therein; a panel to reflect the indicia having windows formed therethrough; and illuminating means behind said windows.

KARL J. MISLIN.
